SHOE SHINING MACHINE

Ralph R. Pagano, 118 87th St., Brooklyn, N.Y.

Filed Aug. 5, 1959, Ser. No. 57,066

Term of patent 14 years

(Cl. D9—2)

Fig. 1 is a front perspective view of a shoe shining machine, showing my new design.

Fig. 2 is a side elevation; and

Fig. 3 is a top plan view thereof.

The rear of the machine is substantially plain.

The essential features of my design reside in the portions shown in full lines.

I claim:

The ornamental design for a shoe shining machine, substantially as shown and described.
